UNITED STATES PATENT OFFICE

1,943,770

PACKAGING MACHINE

Edwin Morey and Robert H. Stimpson, Nashua, N. H., assignors, by mesne assignments, to Frederick L. Emery, Boston, Mass.; Grace H. Emery executrix of said Frederick L. Emery, deceased

Application December 21, 1929
Serial No. 415,683

27 Claims. (Cl. 93—6)

This invention relates to machines for packaging dry, lump, granulated or powdered materials such as sugar, cereals, spices, tapioca and the like. The object of this invention is to provide a novel and improved machine for opening collapsed cartons, gluing and closing the bottom flaps, making and inserting a liner therein, filling the carton, closing and gluing the top carton flaps and ejecting the filled carton, all in a better and more satisfactory manner.

Of the drawings illustrating the preferred embodiment of our invention selected for illustration and description herein,

Fig. 1 is a front elevation of the right hand half of the machine;

Fig. 2, a similar view of the left hand half;

Fig. 3, a diagrammatic view of the driving and other shafts showing the principal driving elements;

Fig. 4, a partial vertical section on the line 4—4, Fig. 1, showing the carton opening mechanism;

Fig. 5, a horizontal cross-section on the line 5—5, Fig. 4;

Fig. 6, a vertical section on the line 6—6, Fig. 4, showing in detail the opening blades and adjacent parts;

Fig. 7, a cross-sectional detail on the line 7—7, Fig. 6;

Fig. 8, a similar view on the line 8—8, Fig. 6;

Fig. 9 comprises three illustrative views A, B, C, in cross-section of the progressive opening of the carton;

Fig. 10, a partial front elevation on an enlarged scale showing the bottom minor flap folding means and defective carton and mispositioned carton detecting means;

Fig. 11, a partial vertical section on the line 11—11, Fig. 1, and, as to position longitudinally of the machine, on the line 11—11, Fig. 10;

Fig. 12, a similar view on the line 12—12, Fig. 1 and Fig. 10;

Fig. 13, a diagrammatic view at station two and approximately the same as Fig. 11, which with

Figs. 14 to 18, similar views at station three, illustrate progressive steps in the gluing and folding of the bottom major flaps;

Fig. 19, a vertical section on the line 19—19, Fig. 1, at station four showing the mechanism for the formation of the liner and its introduction into the carton;

Fig. 19a, a detail, vertical section of the valve controlling the air supply for the supporting of

the paper strip previous to the formation of the liner;

Fig. 20, a cross-section on the line 20—20, Fig. 19, on an enlarged scale, showing particularly the driving mechanism for the paper feeding means;

Fig. 21, a vertical section through the liner forming plunger mechanism and in the same vertical plane as Fig. 19;

Fig. 22, a partial section and elevation on the line 22—22, Fig. 21, showing certain details of the plunger operating means;

Fig. 23, a cross-sectional detail on the line 23—23, Fig. 21;

Figs. 24, 25, 26, diagrammatic views illustrating the several steps in the formation of the minor sides of the liner, the major sides being already formed;

Figs. 27, 28, 29, similar views showing the infolding and sealing of the lower end tabs;

Fig. 30, a vertical section between stations five and six, Fig. 1, showing the liner cooling means operative following the sealing steps, the section line being omitted to avoid confusion;

Fig. 31, a cross-section on the line 31—31, Fig. 10, at station three, showing the carton detecting mechanism operative prior to the formation and introduction of the liner, showing the electrical connections however, diagrammatically, and illustrating also the device of same construction used at station six prior to the charging operation;

Fig. 32, a vertical section on the lines 32—32, Fig. 1, showing the charging mechanism at station seven;

Fig. 33, a cross-section on the line 33—33, Fig. 32;

Fig. 34, a similar view on the line 34—34, Fig. 32;

Fig. 35, a like view on the line 35—35, Fig. 32;

Fig. 36, a detail vertical section on the line 36—36, Fig. 35;

Fig. 37, a detail elevation of the charge leveller, partly broken away;

Figs. 38 to 40 are diagrammatic illustrations showing the turning of the upstanding major flaps at station nine down to a horizontal position, previous to the closing of the liner top at station ten;

Fig. 41, a vertical section on the line 41—41, Fig. 2, showing the liner top folder;

Fig. 41a, a detail plan of the liner top minor flap outlining member;

Fig. 42, a vertical sectional detail on the line 42—42, Fig. 41;

Figs. 43 to 47, diagrammatic figures partly in section, showing the operation of the liner top folding and creasing means;

Fig. 48, a perspective detail of one of the creasing elements;

Fig. 49, a side elevation of the top flap gluing mechanism, with the bed plate in section, on the line 49—49, Fig. 2;

Fig. 50, a vertical sectional detail of the top flap gluing and folding members in the upper part of Fig. 49, with the end plate removed;

Figs. 51 to 53, vertical sectional views through the carton, and liner and adjacent elements showing the steps in the folding of the top minor flaps prior to the gluing and closing of the flaps;

Figs. 54—59, diagrammatic views showing the steps in the gluing operation and some of the steps in the closing operation of the top flaps;

Figs. 60 to 63, illustrate diagrammatically the closing and pressing steps of the major top flaps;

Fig. 64, a vertical partial section on the line 64—64, Fig. 2, showing the carton ejecting mechanism.

Referring first to Figs. 1, 2, our novel machine will be found to comprise a bed plate 1 with supporting legs 2. In this bed is mounted from front to rear, see diagrammatical Figure 3, a main drive shaft 4 in bearings 5, 6, with a driving pulley 7, driven from any convenient source of power, not shown.

On the shaft 4, Fig. 3, is a sprocket 8 carrying a chain 9, Fig. 4, running also over a sprocket 10 on a shaft 13 in brackets 14, 15, on the bed 1. On the opposite end of the shaft 13, Fig. 4, is a sprocket 16 which carries a chain 17, running over a sprocket 18 on a stud shaft 19 in a depending arm 20, near the upper end of the support 21 on the bed 1 for the carton opening means to be described presently. Positioned at right angles to the front of the machine, Fig. 1, and opposite the carton opening means referred to Fig. 4, the machine is provided with any suitable magazine 22 for holding the collapsed cartons 23, preferably such a one as will feed the cartons one at a time to the carton opening means, and as no novelty is here claimed in the magazine per se, it is not shown and described.

In Figs. 4, 5, the carton opening means is shown as comprising a head 24 slidably engaging the support 21 for vertical reciprocating travel therein, a shim 25, Fig. 5, adjustable thereon, being provided to take up any looseness that results from wear.

On its Fig. 4, right hand, or rear face as viewed from Fig. 1, the head 24 is provided with a horizontal slotted plate 26 in which is a laterally movable roll 27 carried by a stud 28 on one link of the chain 17, the construction being like that shown in Figs. 21, 22, for another purpose. By this arrangement, the head 24 is given vertically reciprocating movement, the roll 27 and stud 28 sliding laterally in the slot when, the head having reached the limit of its travel either way, the roll travels about the sprocket 16 or 17, and the head continues its travel thereafter in the opposite direction.

On its opposite face, Figs. 4, 5, the head 24 has a laterally projecting horizontal plate 31 overlying a similar plate 32, part of the carton opening blade carrier 33, the member 33 being carried by the member 31, slidably on member 21, the plates 31, 32 being adjustably secured

by bolts 36 and nuts therefor, see also Fig. 5.

The blade carrier 33, Figs. 4, 5, 6, has secured to its inner or Fig. 4, left hand face, as by screws 39, see Fig. 5, the upper end of a fixed carton opening blade 40 of suitable width, with a bevelled lower edge 41. One edge of the head 33, the right hand one, Fig. 6, is enlarged to form a bearing 43 to receive a short shaft 44 on the lower end of which is angularly carried a movable carton minor side opening blade 45 also with a bevelled lower edge 46, this blade, Figs. 7, 8, normally lying against and within a vertical cut away section 47 of the blade 40.

The shaft 44, Fig. 6, has a laterally projecting stud 48 in cut away section 49 of the bearing 43, the stud carrying a roll 50 normally riding on the vertical face 51 of a cam guide 52. The face 51 turns ninety degrees near the lower end 53 of member 52 and, as the head 33 travels downwardly and after the blades 40, 45 have entered the leading collapsed carton, the pivoted roll 50 follows the curved face of the guide 52, thereby turning the blade 45 ninety degrees to the position shown in dotted lines, Figs. 7, 8, and opening the carton to rectangular form.

The roll 50 is retained against the cam face 51 and caused to follow the curve thereof, Fig. 4, by a spring 54 secured to one end of an arm 55 on the upper end of the shaft 44, while its opposite end is secured to the head 24. These several steps in the opening of the carton are diagrammatically illustrated in Fig. 9, showing the positions of the opening blades.

The head 33 having descended to insert the blade 40 in the carton, as the carton is opened, its outer major wall 59 abuts against a stop plate 60, Fig. 4, depending from the member 33, adjustable as to position, which assists in giving to the opened carton its desired rectangular form preparatory to the next operation upon it by elements to be described.

In the meantime the carton 23 has been pushed further down into the carton carrier 61 by the bevelled inner face of the member 60, and its bevelled lower face of the member 62 and properly seated in the arms 63 of the carton carrier 61, Fig. 4, to be described. The proper positioning of the carton in the carrier 61 is facilitated by a guide 65, Figs. 4, 10, properly mounted for that purpose parallel with the carrier.

As the carton 23 is pushed down into the arms 63, one only being shown here, in Fig. 4, of the carrier 61, Figs. 4, 10, guided by the member 65, the two major flaps 67, 68, the former only shown in this sectional view, straddle the initial minor flap turner 70, Figs. 4, 10, mounted on the bed 1. This member has an inclined top 71 which acts to turn inwardly the rear minor flap 72, as the flap contacts with it in moving downward, the opposite flap 73 dropping vertically down between the end of the member 70 and the adjoining end of a permanent flap turner 74 consisting herein of a flat rod, Fig. 11, also carried on the bed 1. This member turns laterally first the minor flap 73 and later supports the flap 72 as the carton is carried along by the carrier, both flaps finally riding on the member 74.

Before the carton is caused to ride upon the flap turner 74, the carton opener is withdrawn and to avoid any danger of the carton itself being carried upward by the opener, a novel carton stripping device has been provided.

This device, Figs. 4, 10, comprises a carton en-

gaging plate 75 of a size to fit within an opening 76 in the guide 159, the plate being carried on the short arm 77 of a lever 77^a on the guide 159. The long arm 77^b of this lever is connected to a 5 rod 77^c reciprocated by a roll, not shown, on the end of the rod and riding in a cam groove not shown on the cam shaft 79. The cam action is such and so timed that the arm 77^b is free to be drawn downwardly by the spring 77^d and the 10 plate 75 caused to press firmly against the carton in the carrier at station one and to squeeze the carton against the opposite guide 158 and thus prevent the carton from following the carton 15 opener upwardly.

15 But in order to make certain that the carton is properly positioned in its carrier before any further steps are taken toward folding the bottom flaps and sealing them, a novel carton detector or feeler has been incorporated in the machine and is operative as the carton moves to station two, and is shown in Figs. 10, 11 and 12.

This detector, Fig. 11, comprises a cam 78 on the main shaft 79 over which travels a roll 80 on a rod 81 pivotally connected with an arm 82 25 pivoted at one end to bracket 83 adjustably secured to the bed 1, while the opposite arm end 84 overlies the carton carrier 61 and carton. This arm 84, Fig. 10, is forked at its outer end to carry two carton detecting plates 85, grooved on 30 their lower faces, Fig. 11, to receive the upper edges of the opposite major or side flaps 67^a, 68^a of the carton, if in its proper position, and act to hold it there during the bottom flap gluing operation to prevent possible moving of the carton by the gluing members.

On one of the plates 85 is a block 90 having pivoted to it at 91 an insulated circuit terminal 92 from which runs a wire 93 to one pole of a conventional relay switch 94 on any convenient 40 point of the machine, and herein shown diagrammatically.

Overhanging this member 92, Fig. 10, is a circuit terminal in the form of a pin 95, also on the carton opener carrier 31, Fig. 4, conveniently connected electrically to operate the switch. From this terminal also runs a wire 96 to a battery or other source of power 97 and thence to the opposite pole of the relay switch 94.

From this switch run lines 98, 99 to the motor 50 100 and its source of power, not shown. The arm 82 and member 84 are always so timed in action as to be on the way to the low position shown in Fig. 10 in advance of the carton opening blades, and the carton is opened, positioned 55 at station one, Fig. 10, and moved to station two, Fig. 10, before the detector 95 carried by the blade carrier 32 reaches its lowermost position, Fig. 10, in the act of opening a second carton at station one.

60 If the carton is in proper position, Fig. 10, when the pin 95 reaches its extreme low position, the pin will not touch the terminal 92. If, however, the carton at station two, is not in proper low position, but somewhat elevated from any cause, the terminal 92 in its elevated position will contact with the member 95 in its path of travel, and close the circuit, which will cause the relay switch 94 to throw the motor switch to stop the motor, so that the imperfectly positioned carton may be removed from the machine or properly positioned therein.

The pivoted terminal 92 is normally held in position as shown, Fig. 10, by a spring 103, the ends of which are secured to pins 104 on the block 90, and 105 on the terminal 92, but the

spring yields in an emergency of any kind requiring it, and permits the contact 95 to engage and push down the contact 92 without injury to the mechanism.

From station one, the carton is carried to station two by the endless carrier to be described. This comprises, Figs. 4, 11, any convenient member as a sprocket chain 106 of any convenient type traveling in the groove 107 in the bed plate, over sprocket wheels 108 and 109, Figs. 1, 2, at 85 opposite ends of the machine, one end only being shown in each figure. In this case the driving sprocket 109 is at the left of Fig. 2, the delivery end of the machine, see also diagram, Fig. 3, the sprocket on shaft 110 being given intermittent motion by a conventional Geneva gear construction on shaft 110, including the toothed member 111 and socket member 112 on shaft 113. This shaft has a bevel gear 114 meshing with a similar gear 115 on the main shaft 79, driven by the pulley 7 through a bevel gear 116 on the shaft 4, meshing with the gear 117, on shaft 118 carrying also a pinion 119 engaging gear 120 on the shaft 79.

The carton moved to station two by the described carrier with the minor flaps 72, 73 riding on the flap turner 74 comes to rest properly positioned for action thereon by the lower flap gluing mechanism, Fig. 11. The mechanism comprises a reservoir 125 carried by the bed 1, the inner end of the reservoir having an upwardly curved end wall 126. At this end there is rotatably mounted between the side walls of the reservoir a main gluing roll 127 on a shaft 128 rotating clockwise by suitable driving mechanism, not shown, from the front cam shaft 129, Fig. 3.

Also mounted on a shaft 132 in the reservoir is a glue feed regulating roll 133 in contact with the roll 127 and which acts to prevent an oversupply of glue from being carried by the roll 127 to the glue applying rolls to be described. Obviously the excess glue is returned to the reservoir and not permitted to accumulate on the regulator, as in the case with a fixed blue roll scraper or equivalent member.

On the outer end of the reservoir 125 are adjusting screws 136, and nuts 135 on the end of rods 137 which control the position of the bearings for the shaft 132, and thus the position of the roll 133 relative to the roll 127 may be controlled, springs 138 acting normally to keep the rolls in proper contact.

On the brackets 139 on the opposite sides 140 of the reservoir, one only being shown, is a shaft 141 to which are pivoted two parallel arms 142, one only being shown, connected by a rod 143, and parallel shafts 144 rotatable in the arms 142 forming a frame or rack movable about the shaft 141. The two shafts 144 are properly provided with glue applying surfaces and constitute rolls for applying glue to the lower inner carton flap 68. These two shafts cannot contact with each other but are yieldingly held by springs, not shown, permitting greater separation of them to permit a lump of glue or foreign material to pass between them. Such material might be one of the flaps of the carton left between the rolls when the machine was stopped.

The necessary motion is applied to the arms 142 by means of a curved arm 147 pivoted to the shaft 141 carrying a roll 148 which is acted upon by a cam 149 on a shaft 150 which is rotated through gears 151, 152, 153 from the cam shaft 129, Figs. 1, 11.

By means of suitable gears on shafts 150 and 141, but not shown, rotation is imparted to a shaft on and parallel with one arm 142, not shown, which in turn rotates through bevel gears, not shown, the two shafts 144 and their rolls, providing independent motion for them, these rolls with the arms 142 lying normally in dotted line position in contact with glue supplying roll 127, Fig. 11.

10 Accordingly, after the carton 23 has been positioned by the carrier as shown in Fig. 11, at the proper time the mechanism described causes the arms 142 to be swung upwardly and the rolls 144 to apply glue to the opposite 15 faces of the flap 68.

Following the gluing of the flap, the closing of the lower carton end takes place at the next station, number three, as shown through various steps in Figs. 12 to 18 inclusive. It has been 20 customary heretofore to fold the flaps by fixed folding members. This method, however, results in the removal of more or less glue from the flap, leaving it insufficiently glued, and the building up of a coating of hardened glue on 25 the flap contacting members. This results, in turn, in uneven feeding of the following carton with the result that the infolded bottom flaps do no register with each other, and therefore make a poor looking carton.

30 The wet glue usually leaves a deposit on the folding member which defaces the face of the next following flap and particularly when it contains printed matter. In the present case as the carton leaves the folder 74 it slides on 35 to the top of a rocker arm 154, Fig. 10, carried by a shaft 155 not shown in Fig. 1, as it is directly behind the numeral 156, but operated by suitable connections, not shown, from the shaft 192.

40 The glue having been applied as described and illustrated in Figs. 11, 13, the rocker arm 154 receives the carton, see Figs. 12, 14, with a glued flap presser member 156 adjacent one flap, this presser member being mounted on shaft 157, Fig. 1, and operated by suitable connections with the front cam shaft 129.

The rocker arm 154 rotates slowly to the right, Fig. 15, pushing flap 67 to the right, while the presser member 156 rocks and presses flap 50 68 inwardly and upwardly against the minor flaps 73, 72 already infolded by the member 74, the arm 154 traveling downwardly and freeing itself from the flap 67, Figs. 15, 16.

55 The arm 154 starts to return and engages the outer face of flap 67, Fig. 17, the presser member 156 withdraws and Figs. 12, 18, the flap 67 is pressed upwardly against the folded minor flaps 72, 73, and major flap 68, the contact of flap 67 with the edge of the flap 68, Fig. 17, holding the latter in place until the former is pressed firmly up against it from beneath.

The carton having been closed at its lower end it is now advanced to the fourth station 60 for the forming and inserting of the liner. In order that the carton may be kept in as near as possible its proper shape during the action of the several elements upon it while performing their various functions, there are provided longitudinal guides 158, 159, Figs. 1, 10, between which the cartons travel from one station to another. These guides are secured to brackets, 70 171, 182, on the bed plate 1.

At station four, however, these guides are 75 interrupted and a space left between their ends

in order, for one reason, that the carton at this station may be removed, if imperfect, or if, for any reason, that should be necessary, before the liner forming mechanism operates. To take the place of the permanent guides however, at the points where they are removed, there are provided removable guides. Adjacent the outside of the carton there is a short guide 160, Fig. 19, in line with guide 158, and which, by means of ears 161 thereon is pivoted to an arm 162 pivoted to 163, Fig. 19, to the bed 1.

This arm 162, Fig. 19, is yieldingly held in position closely against the carton wall by springs 164 one end of each of which is secured to the arm 162 by rod 165, the opposite ends broken away, being similarly secured to the bed 1. The arm 162 is provided with a short rod 167 for manually operating the removable guide. On the opposite and rear side of the carton the break in the permanent guide 159 is supplied by a second removable guide 168 of similar shape, pivotally carried by a lever 169 on a shaft 170 in suitable brackets secured to the bed 1.

25 The lever 169 is yieldingly held with the guide in proper position by a spring 172, broken out, secured to the lower lever end and the support 173. By the described means, it is possible to remove, if necessary, at this station, any improperly held or imperfectly opened carton before the liner is placed therein.

30 These two guides 160, 168 perform a second important function as strippers to assist in removing the liner, when completed, from the plunger as it is withdrawn upwardly. The pressure created by the spring 164, 172 causes the 110 guides to grip the liner and carton firmly to that end.

35 Preparatory to the operation of the liner forming mechanism at the fourth station, I will describe a novel carton detecting or feeding means 115 operative at the third station effective upon the carton when it arrives at station four and designed to prevent the operation of the paper cutting members in case the carrier advanced to station four bears no carton or an imperfectly 120 formed one.

40 Secured to the guide 159, Fig. 31, is a plate 174, having mounted thereon at 175 a fell crank lever 176, the elbow 177 of the long arm of which normally contacts with the wall of the carton 125 23 if normal in outline and in proper position.

The short lever arm 178 carries at its end an electrical contact member 179. On the plate 174 there is also a post 180 carrying at its end an electric terminal 181 protected by insulation 182. From this terminal runs a wire 183 to a magnetic switch 184 here shown diagrammatically. From the post 180 also runs a wire 185 to a battery 186 of low voltage, say 24 volts, and thence to the switch 184. From the opposite 135 side of the switch run wires 187, 188 to a solenoid 189, Fig. 19, on the bed 1, and in a more powerful circuit, for instance 110 volts, derived from any suitable source, not shown. This solenoid 189 is operatively connected, as will be 140 described presently, with the liner forming mechanism.

45 If now the lever arm 177 when in full line position contacts with a carton as it travels along in its carrier, then the paper cutting mechanism functions normally, as intended; but if the arm 177 fails to engage a carton when in full line position, then it swings inwardly to dotted line position in the path of the carton, the contact 179 is caused to engage terminal 181, closes the 150

circuit through switch 184 and thus acts to prevent operation of the paper cutting mechanism, as will be presently described.

In order to prevent the arm 177 from dropping between one arm 63 and corresponding arm of the succeeding carrier that may not be close together as in the case when the carton is a narrow one, and the arms 63 separated, we provide them with ears 190, Figs. 1, 10, which are sufficiently close together to prevent operation of the detector mechanism in normal cases.

It will be noted here, Fig. 31, that the carton is slightly distorted in shape at its minor sides by the inclined inner faces of the carrier arms 63, and this is to offset the natural tendency of the carton to return to its folded position, and to retain it in as nearly as possible correct shape for the liner mechanism.

On the bed 1, Fig. 1, and at station four, see also Fig. 21, is a tall housing 195, for the liner forming plunger 196, and provided with bearings 197, 198. Power for operating this plunger is provided, Fig. 3, through a sprocket 199 on the shaft 4, carrying a chain 200, dotted lines, Fig. 21, running over a sprocket 201, Fig. 21, on a shaft 202 mounted in bearings 203, 204, in support 205 on housing 195, on the bed 1. Shaft 202 carries at its, Fig. 21, left hand end, a sprocket 206 which, in turn, carries a chain 207 running over a second sprocket 208 in the bearing 209 on the housing 195. This chain 207 drives the plunger 196, Fig. 22, by means of a lug 210 on the chain 207, which lug carries, pivoted thereon, a roll 212 in a slot 213 in the housing 214 secured to the plunger as by screws 215.

As the chain travels upwardly, obviously it will carry the plunger likewise, the roll 212 moving laterally in the slot 213 as the lug 210 moves about the sprocket 208 clockwise, and then, descending to and about sprocket 206 in the same manner carrying the plunger downwardly and again upwardly as before.

The first step in the formation of the liner is the furnishing of paper of proper width in the form of a strip 220, Fig. 19, from a roll 221 supported in a bracket 222 on the rear of the bed plate 1. This strip passes first beneath a valley roll 223 journaled in a slotted post 224 on the bracket 222, and is then fed between feed rolls 225, 226 rotated by change gears from the shaft of roll 227, not shown, and thence between the supporting roll 227 and cutter roll 228 provided with a cutter 229, to cut the paper at the proper point as to its length. The rolls 225, 226 are carried on a rearwardly extended bracket 230 on the bed 1.

The roll 223 acts to prevent the formation of wrinkles in the paper and drops in the slot in the post as the size of the paper roll diminishes. As the paper strip 220, Fig. 19, cut as described, passes over the table 232, it travels beneath pressure rolls 233 in a rack 234 with a curved end 235 hinged at 236 to the support 237 on the bracket 230. This serves to keep the paper flat and in proper position for feeding to the plunger beneath guides 238, 239.

The roll 227 and cutter 228 are geared to be rotated normally by a chain 240 from a sprocket 241, Fig. 20, fast on the shaft 242 suitably mounted in bearings 243 on the bed 1. The sprocket 241 and the shaft 242 are driven by a disk 243^a fast thereon, through a disk 244 loose on the shaft 242 and fast to a sprocket 245, also loose on the shaft, which sprocket is driven con-

tinuously by a chain 246 from a sprocket 247 on shaft 79, Fig. 19. The disk 243^a is driven from disk 244 by means of a pawl 250 on the latter, under controllable means.

To control rotation of the rolls 227, 228 from the disk 243^a by means of the pawl 250 we provide the solenoid 189 operated by the carton feeler already described. This solenoid, Figs. 19, 20, operates through an upright rod 251 connected to the end of the arm 252 mounted on the block 253 on the bed 1. On the stud shaft 254 in the block 253 and beside arm 252, Fig. 19, is also a lever 256, Fig. 20, which normally lies in the plane of but below the path of the end 258 of the pawl 250 on the disk 244, Fig. 19. The pawl 250 is normally held in position as shown, by a spring 257, one end of which is secured to the pawl, while the opposite end is secured to a pin unnumbered on the disk 244. The lever 256 carries the spring 259 secured to it and the post 230 by which the forward lever end is normally held in low position and inoperative. When the solenoid 189 is operated by the lever 176, Fig. 31, on failure to find a carton in position as described, the lever 256 is raised by the rod 251, 100 causing the forward end of lever 256 to engage the end 258 of pawl 250 to throw it out of engagement with disk 243^a and stop rotation of shaft 242, sprocket 241 and chain 240 driving the rolls 227, 228, and the feeding of paper to 105 the plunger, thus permitting any adjustment of or attention to the carton. The main reason for desiring to stop the cutting of the paper is to prevent the making of a liner when there is no carton or only a damaged one.

The paper strip severed by the cutter 229, Fig. 19, is fed to the plunger 196 by a belt 260 over pulley 261 driven by pulley 262 on shaft 263, driven in turn by a chain 264 from sprocket 265, Fig. 20. This sprocket is loose on shaft 242, but 115 fast with sprocket 266 also loose thereon and driven by sprocket 266^a on the shaft 79.

The paper strip 267, dotted lines, Fig. 24, from which the liner is to be made is now fed beneath the plunger 196, Figs. 19, 24, and presently the 120 plunger descends and forces the paper down between the front and rear liner forming walls 270, 271, Figs. 19, 24, secured to brackets 272, 273, Fig. 19. This action forms the major carton walls.

To prevent the paper from sagging into improper position before the plunger engages it, we provide means for discharging a mild stream of air into the liner forming chamber and path of the plunger beneath the paper strip 267, Fig. 130 19, from an outlet 274 through the walls of the chamber. Air is supplied for this purpose from any convenient tank, not shown, through a pipe 275, Fig. 30, leading to a valve 276, Fig. 19^a, on a support 277 on the front of the machine, see 135 Fig. 1. The slide valve 276, Fig. 19^a, is operated from a cam 278 on the shaft, Fig. 1, by means of a rod 280 at the proper time. When the valve is in its position, Fig. 19^a, it is inoperative, but when the valve is drawn downwardly, the passage 140 281 therein will connect the pipe 275, to the outlet 274 beneath the plunger and support the paper strip in proper position for action by the plunger.

There is also operative at this point and time, 145 that is, when a sheet of paper is fed to the plunger, a sheet positioning means, Fig. 1, including a cam 281 on the front cam shaft, a roll 282 on a rod 283 in operative connection therewith running up to an arm 284, Figs. 1, 19, on a 150

shaft 285 in brackets 286 on the supports 243. From the opposite ends of this shaft extend upwardly two rods 287 carrying at their upper ends a horizontal rod 288 on a level with and parallel with a like rod 289 permanently positioned, Fig. 1, to line up the paper. If the sheet has been, for any reason, not fed adjacent the bar 289, then the bar 288 will, when rocked laterally by the rod 283 described, push the sheet laterally 10 against the bar 289 to proper position.

For forming the minor or narrow carton walls, we have provided novel means comprising, Figs. 19, 24, 25, 26, swinging wall forming plates 290, 291, adjacent the wall 270 and plate 292 adjacent 15 wall 271. These plates are carried on the opposite ends, Fig. 24, of stud shafts 293 in the brackets 272, 273, Fig. 19, but not shown in Fig. 24. The shafts 293 carrying plates 290, 291, Fig. 24, are connected by arms 294 and a link 295 and they and the shaft carrying the plates 292 each have dogs 296 extended into the path of the plunger.

20 In the edge of the table 232 and on each side of the plunger is a roll 297, Fig. 24, backed by a spring 298 to facilitate uniform movement of the paper beneath the plunger.

When the U-shaped strip of paper backed by the plunger in its downward travel reaches a point slightly below its position as shown in Fig. 24, it engages the dogs 296, turns them downwardly and their rear ends upwardly throwing the plates 290, 291, inwardly and downwardly and causing them to bend the opposite projecting edges of the paper strip inwardly, Fig. 26, 25 against the plunger.

Immediately after the edges of the bent strip of paper have been folded inwardly, as stated, the paper and enclosed plunger engage the dogs 296 on the opposite side, depress them and cause 40 the plates 292 to fold inwardly the edges of the opposite side of the paper strip, Fig. 27, thus forming the minor liner walls and leaving the triangular minor wall folds or tabs 299.

At their lower ends, Figs. 27, 28, the brackets 45 272, 273, not shown, carry front and rear folding bars 300, 301 respectively, between the ends of which are suspended hollow bars 302, 303, Fig. 28, each containing a heating unit 304, the four members 300, 301, 302, 303 forming a rectangular liner sealing means with curved edges adjacent 50 the minor walls, which curved edges and members 302, 303, Figs. 25, 28, 29, are heated by any convenient means as electricity through wires 305 connecting with any convenient source of 55 electricity, not shown.

As the tabs 299 and overlapped minor liner walls move downwardly past these heated members 302, 303, the tabs and overlapped edges are warmed sufficiently through heating elements 304 60 therein, and by the enclosed plunger 196 and its heating member 304^a, Fig. 23, connected by wires 305^a leading from the top of the plunger 196 to any convenient source of electricity, not shown, to cause the paraffin or other material on the 65 paper to soften. The liner edges are pressed together, the tabs 299 are pressed closely against the liner minor walls, and as the parts cool they adhere firmly together. The plunger head side walls, Fig. 23, are fluted as at 306 to reduce the 70 tendency to adhere to the paper, also to admit air to offset the tendency to form a vacuum on the withdrawal of the plunger, and the sides have steel bearing parts 307 to take the wear of the elements 296 thereon.

75 The elements 302, 303 are held yieldingly in

carton contacting position by springs 307, Fig. 1, seated between the ends of the members and suitable stops on the ends of the elements 300, 301, the ends of the former protruding through and sliding in the latter.

As the liner is forced between the tab and fold sealing elements described, it is positioned by the plunger in the carton 23 beneath it, Fig. 19, with its top projecting above the carton. As there is no bottom support in the carrier for the 80 carton, a yielding one is provided, Fig. 19, to take up the pressure of the plunger if necessary and prevent injury to the liner, and to cause the 85 warm liner to adhere slightly to the bottom of the carton, in the form of a block 308 in a cylinder 309 on the bed plate 1, the block being 90 yieldingly supported by a spring 310 in the cylinder and normally supporting the block 308 in proper position.

At stations five and six we have provided 95 means to assist the quick cooling of the liner which was warmed to some extent to effect the sealing operation of the overlapped side edges and triangular tabs. This means, Fig. 30, comprises an air conducting pipe 275 leading from a 100 convenient source of cool air not shown, which may, by a conventional blower, not shown, be conveyed through pipes 311, preferably four in number, into or near the four corners of the open liner top.

This cooling operation is controlled by a slide 105 valve 312 in a body 313 suitably mounted on the support 243, Fig. 1, the valve having a port 314 adapted to register at stated times with the ends of the pipes 275 and 311.

The action of this valve is controlled by a vertical lever 315 conveniently mounted for swinging action about a pin 316, the lower end, Fig. 30, of the lever carrying a roll 317 which is normally maintained in contact with the face of 115 a cam roll 318 by a spring 319 secured to the upper end of the lever and the valve body 313. The cam is on shaft 242 and timed to open the valve immediately upon the arrival of the carton at station five and continues while it is at station 120 six.

The liner is now advanced in its carton to station seven to be charged with material. Preparatory thereto, however, at station six, a second carton detector not shown, as it is on the 125 rear of the machine, but like the one already described, Fig. 31, for determining the presence of the carton previous to the formation of the liner, is operative at this point to determine the presence of a carton because, if there is no carton, the charging mechanism should not be operated.

Inasmuch as the detector is identically like the one already referred to, it seems unnecessary 130 to again illustrate and describe it as it is illustrated and described in connection with Fig. 31, and with the charging means at the proper time in connection with the operation of the latter.

It having been determined that the carton is 140 in proper position to receive its charge of material beneath the discharging spout 320 of a hopper 321 of the charging apparatus, this mechanism will now be described. This apparatus includes an upright bracket 322 adjustably 145 secured to the bed plate 1. The bracket has a laterally extended arm 323 overhanging the machine and in the arm is journaled a hopper carrying shaft 324 operatively connected with the driving shaft 325 mounted in the base 1 and hav- 150

ing on its lower end a worm gear 326 meshing with the worm 327 on the shaft 79.

The shaft 324 is carried in a hub shaped bearing 328 on the arm 323, and which carries the depending chute already referred to. On the upper end of the bearing 328, Fig. 32, is any suitable ball bearing 329 supporting a collar 330 fast on the shaft 324 and carrying the disk 331, with a plurality of apertures about its edge. In each of these apertures is a collar 332 which receives slidably in its upper end the inner end of a sleeve 333 in the bottom of the hopper 321 referred to and which is held fast by a nut 334 and flange 335 on the upper end of the screw 336 threaded into the end of the shaft 324 and rotating therewith. The hopper may be adjusted as to height relative to the plate 331 by adjustment of the screw 336 relative to the shaft 324 and locked by the lock nut 337.

Within the hopper there is a reservoir 340 carried by and depending from an arm 341 on a bracket 342 in turn adjustable on the bracket 322 by means of nuts on opposite sides of the rib 344 on the bracket. The reservoir 340 has a slide 343 near its lower end to control the flow of material therefrom to the hopper 321.

The bracket 342, Figs. 32, 33, also carries a sprocket 345 on a shaft 346, a chain 347 running from the sprocket down to the sprocket 348, on the lower end of the bracket 322, thence around the driving sprocket 349 on shaft 79, thence to sprocket 350 and return to sprocket 345, sprockets 348, 350 being carried on the end of a bracket, not shown, adjacent bracket 322, and adjustable on the bed 1.

On the opposite end of the shaft 346, Figs. 32, 33, is a bevel gear 351, dotted lines, in mesh with a similar gear 352, dotted lines, on the lower end, Fig. 33, of the shaft 353, Fig. 32, carrying on its upper end a sprocket 354, Fig. 33. About the sprocket, Figs. 32, 33, runs a chain 355 to a sprocket 356 on a shaft 357, Figs. 32, 33, carried by the laterally extended arm 358 on the bracket 342.

The shaft 357, Fig. 32, extends down into the hopper 321 directly over the circular path of travel of the sleeves 333 and carries on its lower end a novel material charge leveller 360. This leveller, Figs. 32, 37, is in the form of a hollow cylinder having spiral grooves 361 running upwardly in its outer wall, and is positioned to nearly touch the bottom of the hopper. The material flows from the reservoir 340 to the hopper 321 and gravitates to the lower portion thereof in such quantity as to fill the several sleeves 333, which, with the disks to be described, may be said to form cups, with material, as each cup arrives at the lowest point in its path of rotation.

As each cup in its upward travel, Fig. 33, arrives beneath the leveller 360, the latter rotates thereover and levels the charge to the bottom of the reservoir so that all charges are of uniform size. As the leveller rotates, the surplus of the charge is caused to travel up on the outside thereof in the grooves 361 and is thrown laterally beyond and below the baffle plate 362 and gravitates downwardly to the cups at the lower portion of the hopper, and we thus avoid cutting and otherwise breaking and scratching the grains or pieces of material, which happens if the leveller simply rotates among them in one place and pile.

To prevent any material from escaping the action of the leveller and moving upwardly to-

ward the discharge chute, we provide, Fig. 33, the curved baffle plate 362 already referred to, which accomplishes the desired purpose.

The disks 363, Figs. 32, 33, 34, 35, which form the bottoms of the cups already referred to as they close the ends of the sleeves 333, and the operation of which control the delivery or non-delivery of a charge of material, are carried upon the long arms, Figs. 32, 34, 35, of levers 364 pivoted at 365 to the plate 331.

The short arms of these levers each carry a roll 366 on its lower face, Figs. 34, 35, 36, which roll normally travels against the upturned circumferential edge of the plate 367 on the arm 323, and when so traveling, Figs. 34, 36, the long arm of lever 364 with its disk 363 will be positioned, Fig. 32, directly beneath the lower end of one of the collars 332 in the plate 331 and with it and the sleeve 333 above it form the cup already described to hold the charge of material. In order, however, to swing the disk away from the cup and thereby dump the charge into the liner as each cup arrives over a carton, the edge of the plate 367, Fig. 34, is cut away at the proper point adjacent each collar and provided with a narrow angular plate 368, Figs. 34, 35, forming a cam surface. The roll 366 is caused by this cam and a switch plate member 369 pivoted at 370 on the disk 331 when actuated as will be described, to move inwardly and thus swing its disk outwardly, Fig. 34, away from and to open the end of the sleeve or bottom of the cup over the chute 320 and dump its charge into the liner.

The cam plate 368, Fig. 35, will thereafter cause the roll 366 to travel outwardly about the edge of the plate 367 and swing the disk back into normal position to again form a cup by closing the end of its sleeve.

This closing action is so timed that it happens late enough to allow the cup to entirely dump its contents but early enough to be fully closed again before the material begins to flow again into the cup from the hopper, thereby preventing any spilling or jamming of the material. The control of the switch 369 is in the detecting mechanism referred to, Fig. 31.

To effect the purpose of the detector heretofore referred to, Figs. 31, 35, and automatically control the action of the disk in respect to dumping its charge, the plate 367, Fig. 35, has a novel connection with the solenoid 374 on the plate 367, the switch 369 being normally open, Fig. 34, so that the roll 366 will pass inside it.

The stud shaft 370 on which the switch is mounted, however, Figs. 34, 35, carries fast on its lower end an arm 372, the end of which is connected pivotally to the armature 373 of the solenoid 374 on the lower face of the plate 367. When the detector already described indicates the nonpresence of a carton ready for a charge, it automatically draws inwardly the arm 372, and the rod 373 of the solenoid, swinging the switch 369 inwardly.

This action, Fig. 35, closes the cam path, causing the roll 366 to continue its travel about the outer edge of the plate 367 without swinging the disk 363 on its lever arm away from the collar 332 and dumping the charge of material. As soon as the carrier leaves its position beneath the cup 332 and a suitable carton is presented to the detector, the circuit through the relay switch and solenoid is broken and the switch 369 is opened to normal position, Fig. 34, by the roll 366 travelling over the rear end of

the switch about the disk 367. Rotation of the hopper bringing the next roll 366 to the switch 369 will find the switch open and cause the roll to travel over the cam surface inside the switch 370, and again dump the contents of the next cup. The lever 364 is prevented from swinging inwardly at any time by the stud 376 in the bottom of the plate 331. The outer end of the arm 372 is held seated in the depression 377 in the 10 arm 378 on the disk 367 by the action of the spring 379 seated on the lug 380 to ensure the switch being wide open or fully closed.

In this manner, should a carton in imperfect condition for any reason be encountered or 15 should there not be any carton and liner, the annoyance and waste of dumping a charge therein will be avoided and in the case of some materials, and from consideration of cleanliness, this is a very important advantage.

20 At station eight, the charge is tamped into more compact condition within the liner. For this purpose, Fig. 2, a plunger 382 with a suitable head 383 is actuated by a cam not shown on the main cam shaft 129 through a connecting rod 25 384 for the purpose. No novelty in the tamping alone is claimed, but its action in combination with the other elements is believed to be novel.

Following the tamping operation and in the 30 period while the carrier is advancing from the eighth to the tenth stations, the top of the liner is infolded. The first step is the turning down to horizontal position of the two major carton flaps 67^a, 68^a, which, to this point, have been perpendicularly positioned and guided by the 35 channeled guides 385, Fig. 2. The guides begin at about station three on the machine and are mounted to partly overhang the path of the cartons. At station eight, Fig. 2, the outer flange 386 is cut away and from this point each guide 40 blends into a flat strip and curves downwardly gradually to a horizontal position, Figs. 38 to 40. At about station ten on the machine, the flat guide ends, and at that point there is positioned on the guides 158, 159 a horizontal 45 U-shaped member 388 to receive and hold down the carton major flaps 67^a, 68^a to prevent them from springing upwardly again and thus interfering in any way with the operation of infolding the liner flaps.

50 At this point the opposite major liner flaps 403, 409, Fig. 41, are acted upon first by a rear liner flap folder 390 in the form of an arm with a foot 391 which is forced forward and down by the action of a roll 392 on a rod 393 and traveling in a groove 394, in the cam 395 on the cam shaft 79. The rod 393 is yieldingly connected by a sliding rod 396 and spring 397 with a yoke 398 connected to the arm 399 of the lever 400 pivoted to the bracket 401.

60 The foot 391 carries on its opposite ends, a shoe 402 for the initial forming of the minor liner upper tabs preparatory to the infolding of them, Figs. 41, 43. This foot 391 swings inwardly and engages the rear upstanding major flap 403 of the liner, and with the aid of the shoe 402 folds it in and down over the top of the charge, leaving the minor liner flaps 404, 405 partly folded inwardly, Figs. 41, 43, of triangular 65 shape. This shoe 402, Fig. 41^a, has a flat top 405^a forward beveled edge 405^b and forwardly directed angular face or edge 405^c, the top being undercut from the rear. Next a like foot 406 with a plate 407, Figs. 41, 44, on an arm 408 70 75 performs the same operation on the opposite up-

standing major liner flap 409 leaving upstanding a loosely folded triangular shaped tab, Fig. 44.

The foot 406 is provided, Figs. 45, 46, at opposite ends with upstanding triangular shaped plates 407. This foot is carried, as stated, on an arm 408 of the lever 411, Fig. 41, pivoted at 412 to the web 413 of the bracket 414 on the bed 1 and a short arm 415 of the lever is actuated by connections like those described with reference to arm 390, from a cam 416 on the cam shaft 129 with a groove 417 in which travels a roll 418. After the infolding of the two major liner flaps and before the withdrawal of the foot 406, novel means have been provided for pressing and closely creasing the two remaining oppositely tapered upstanding triangular shaped minor flaps, 404, 405.

90 For this purpose also there is provided, Fig. 41, at each side of the arm 408 an arm 410 pivoted at 420 to the bracket 414. On the pin 420 is an arm 422 also actuated by similar connections 423 and roll 424 on the cam 424^a, Fig. 1, on the cam shaft 129.

95 These two long arms 410, Fig. 42, are connected for mutual support by tie bars 425. Each arm 410 has pivoted thereto near its upper end, Figs. 41, 42, 46, 47, a short lever 426 mounted on studs 426^a, carrying on its front or long arm 427 a novel flap pressing member designed to cooperate with the plate 407, and on the opposite sides of the flaps 72^a and 73^a of the liner to press the same between them, and cause them to stand upright, Fig. 45. This member, Figs. 45, 46, has an outer or side face 429, with the top tapered downwardly at 430, and front tapered outwardly at 434 so that a bevel face will pass beneath and engage the lower face of the partly upstanding carton minor flaps, 72^a, 73^a, to press them both upwardly and inwardly against the liner flaps 404, 405 and plate 407. This member is shown in perspective in Fig. 48. Each arm 410, Figs. 46, 47, has also a short supporting arm 437 pivoted thereto at 426^a to reinforce the arm 427 laterally as it presses against the tab and plate 407.

100 The arms 427 with the blocks 429 thereon are caused to move in the required path with but a short swing of the arms 410 by a roll 431 on the rear arm of the lever 427 travelling beneath and against the lower face of a cam member 105 435, dotted lines, Fig. 41, while the opposite arm of the lever is drawn down by a spring 436 secured thereto and to the arms 410.

110 The members 388 are cut away at 438 to permit necessary travel of the arms 408, 395 without interference.

Carton top flap closing

115 The carton and liner minor flaps now upstanding are ready to be infolded or inturned. For this purpose we have shown, Fig. 2, a rotary tab folding member 440 commonly termed a pigtail on a hub 441 on shaft 476 and operated by suitable gear mechanism not shown from the front cam shaft 129. This mechanism is timed 120 so that the member is in position shown, Fig. 51, and stationary when engaged by the approaching minor carton flap 73^a, Fig. 52, and as the flap strikes it, the flap is bent backwardly and downwardly sufficiently to enable it to slide 125 beneath the fixed turner 443 suitably supported in its path.

130 As the movable minor flap turner 440 rotates the low portion 444 leaves the flap, and the outer end 445 of the pigtail member shown 135

A top carton pressure plate 500 with ribs 501 on its lower face is carried by an arm 502 which, by suitable means actuated from any convenient point, not shown, is caused to drop 6 and lightly contact at the proper time with the unglued upper face of the major flap 67^a, Fig. 61, while the opposite major flap 68^a, glued on its inner face as described, is gradually brought by contact with a progressively curved guide 503 10 to an upright position, Fig. 62, from the angular position. As the carton moves in the carrier, it passes, Figs. 62, 63, from beneath the ribbed surface of the presser 500 to beneath the rolls 504 adjacent to but on the opposite end of the 15 presser 500.

Station fourteen

Here the carton is positioned in front of the 20 ejector directly opposite laterally running flap pressing and delivering belts 505, 506, running over pulleys 507, 508 and idlers 509, Fig. 62, mounted for limited vertical movement, and positioned above the lower run of the upper belt. There is also provided a plate 510, Fig. 64, for 25 supporting the upper run of the lower belt 506.

The ejector for delivering the carton, Fig. 64, comprises a plunger 511 slidable in a bracket 512 to the side of which plunger is pivoted a link 513, the opposite end of which is connected 30 to the long arm 514 of a lever 515, while the short arm 516 of the lever carries a roll 517 which travels in a groove 518 in the side of the cam 519 on the shaft 129.

The foregoing described machine through the 35 cooperation of the various described groups of mechanism and novel features provides the most efficient, simple, least expensive, rapid and satisfactory service we know of for packaging material in sealed containers.

40 Our invention is not restricted to the embodiment thereof illustrated and various changes therein may be made within the scope of the appended claims.

45 It is to be understood of course that the reference to the use of glue herein is general and not specific and the specification comprehends the use of any suitable adhesive for the purpose specified.

We claim

50 1. In a packaging machine provided with a carton feeding magazine, the combination therewith of carton opening means acting also to position the carton opened and parallel with the path of travel through the machine, and 55 an endless carton conveyor, a bed plate having thereon for successive operation lower minor flap folding means positioned in the vertical and lateral paths of the carton and arranged to infold said flaps, and lower major flap two 60 side gluing means operative while the carton is stationary comprising a feeding member and independently driven applying members radially equally positioned from the feeding member acting in an upward path upon two faces of the 65 downwardly extended flap; and liner forming and inserting means and means for folding and means for closing the liner top and some of the carton top flaps, and gluing means operative upon the remaining carton flaps over the liner top; and means for folding the carton flaps.

70 2. In a packaging machine provided with a carton feeding magazine, the combination therewith of carton opening means, a bed plate with an endless carton conveyor, having thereon for successive operation lower minor flap folding

means positioned in the vertical and lateral paths of the carton and arranged to infold said flaps; lower major flap two-face gluing means comprising a feeding member and independently driven applying members acting in an 80 upward path upon the downwardly extended flap two-face, oppositely rocking lower major flap infolding and pressing members; means including a liner forming pocket, paper cutting members a liner forming plunger and folding members actuated thereby, and liner warming means above the carton carrier to fashion the liner, seal it, and insert it into the carton, and operating means therefor.

3. In a packaging machine provided with a 90 carton feeding magazine, carton opening means, a bed plate and an endless conveyor in combination with lower flap gluing and folding means, upper flap gluing and folding means, liner forming and inserting means and carton detecting means for determining the presence of a 95 carton before making the liner, comprising paper feeding and cutting means control, including an electric circuit with a solenoid and a member mounted normally therein to swing into contact with a carton, if in proper position in the carrier, and otherwise to swing across the path of the carton, close the electric circuit, actuate the solenoid, and stop the paper feeding means.

4. In a packaging machine provided with a 100 carton feeding magazine, carton feeding means, an endless conveyor, lower flap gluing and folding means, liner forming and inserting means including a plunger, and paper wiping and folding members for forming the liner about the 110 plunger, the combination therewith of a bed plate having thereon in operative relation carton detecting means operative with the carton in its carrier, carton charging means and carton detecting means in connection therewith 115 including an electric circuit with a solenoid therein connected to the charging means, and a carton engaging member constructed and arranged to contact with the carton if in normal position without change in the circuit and if 120 the carton is not in normal position, to close the circuit and lock the charging means in inoperative position.

5. In a packaging machine provided with a 125 carton feeding magazine, carton opening means, an endless conveyor, flap gluing and folding means, liner forming and inserting means, carton detecting means and carton charging means, in operative relation the combination therewith of a bed plate having thereon upper liner flap 130 folders comprising arms for engaging the liner on opposite sides to infold the major flaps and form erect minor flap tabs, creasing means for the latter constructed and arranged to press the tabs between creasing members and major flap 135 folders, and top carton flap gluing and folding means, and carton ejecting means arranged for progressive action on the carton.

6. In a packaging machine provided with a 140 carton feeding magazine, carton feeding means, an endless conveyor, lower gluing and folding means, liner forming and inserting means including a plunger, liner blank positioning means and air current blank supporting means, and paper wiping and folding members for forming the liner about the plunger, the combination therewith in operative relation of carton detecting means relative to the carton in its carrier, carton charging means and carton detecting means in connection therewith includ- 145 150

broken away, Fig. 51, positions itself above and in the rear of the opposite minor flap 72^a. Progressive rotation of the member 440 brings its end 445 in contact with the back of the flap 72^a, Fig. 52, and causes it, Fig. 53, to be folded inwardly and downwardly, by the intermediate portion of the pigtail 446.

As both minor flaps 72^a, 73^a are passed beneath the member 443 to the left, Fig. 51, by the carrier, the flaps are bent down flat upon the top of the liner carrying with them the liner tabs 404, 405, Fig. 53, preparatory to the action of the top gluing means.

15 Top gluing mechanism

This mechanism, Figs. 49, 51, includes a main glue supply roll 450 mounted in the walls of the reservoir 451 on a shaft, not shown, but in alignment with shaft 452, and is rotated by means of a disk 453 fast on the shaft 452. The disk receives a pin 455, dotted lines, Fig. 49, on a gear 456 on the shaft of the roll 450, which gear is also in mesh with a smaller gear 457 on a shaft 458 carrying a glue regulating roll 459 adjacent the feed roll, and by this means the roll 459 is rotated.

The roll 459 is mounted in arms 460 pivotally suspended from sides 461 of the reservoir. The lower ends of the arms carry rods 462 which extend through the ears 463 on the reservoir walls and carry adjusting nuts 464 and lock nuts 465 by means of which the position of the roll 459 relative to the main roll 450 may be determined, to control the quantity of glue that the latter roll shall carry up from the reservoir to the applying roll 479, to be described, so that the supply may at all times be adequate and uniform, but not greatly in excess of the requirements.

Provision is made, however, Fig. 49, including a spring 466 about the rod 462 and suitable seats therefor, by means of which the rod is held yieldingly in its position, so that if a lump of hard glue or foreign matter for instance, is picked up by the roll 450, it may yield relative to the roll 459 by the sliding of the rod 462 and permit the hard substance to pass between the rolls without injury to them.

The shaft 452 carries a sprocket wheel 466 over which runs a chain 467 from an idler 468 and a sprocket 469 on the drive shaft 129 by means of which the mechanism is driven.

On a shaft 472, Fig. 49, at the top of the reservoir is a gear 473 in mesh with a smaller gear 474 which is pinned fast to a gear 475 both running loose on the shaft 476, gear 475 in turn meshing with a gear 477 on a shaft 478 carrying the glue applying roll 479, Fig. 50, the shaft 478 being carried by curved arms 480 pivotally mounted upon a shaft 481 in the radial arms 482 fast on the shaft 476.

60 The arms 480 and roll 479, Fig. 50, are yieldingly held in desired position by helical springs, not shown, secured to the ends of the cylindrical flap presser 483 to be referred to, on the shaft 476 and at their opposite ends to the extended ends of the ribs 484 respectively.

This construction permits rotation clockwise of the roll 479 on the shaft 478, and limited swinging movement of the roll and the arms 480 about the shaft 476 when, during the application of the glue to the carton flaps, the roll 479 on shaft 478 rides up on a track 485, Fig. 56, on the inner wall of the support for the shafts 476, at one point during the rotation and travel of 75 the roll 479 about the shaft 476 to avoid crush-

ing of the top edge of the minor carton walls and minor flaps 72^a, 73^a.

The arms 480 carry on their outer ends the curved segmental flap pressing member 483 referred to, which is adjustable in its circumferential relation to the member 487 by means of a set screw 488 in the ends of the member 483 bearing on the radial rib or arm 489 of the presser member 487, and in connection with the springs heretofore referred to but not shown.

80 For the purpose of infolding the inner top major flap 67^a or the one adjacent the glue roll, we have provided means comprising a series of curved fingers 490 on the ends of ribs 491 on the outer face of the arcuate yielding flap presser 483 on the arm 480, similar ribs 492 being provided on the narrow circumferential surface of the presser member 487.

85 For the purpose of infolding the inner top major flap 67^a or the one adjacent the glue roll, we have provided means comprising a series of curved fingers 490 on the ends of ribs 491 on the outer face of the arcuate yielding flap presser 483 on the arm 480, similar ribs 492 being provided on the narrow circumferential surface of the presser member 487.

90 While the glue applying roll 479 is always rotating on the shaft 458, the flap folding fingers 490 have intermittent motion in harmony with the action of the carton conveyor and are so actuated by any suitable mechanism: such as a suitable Geneva gear construction, Fig. 3, and connections, not shown, and which need not be 100 here described.

95 As the cartons are presented to the upper major flap folding members for folding, the minor flaps having been infolded as described, Figs. 43, 47, the following operations follow in 105 the order described: The rear end of the reservoir 451 is provided with an end 493 overhanging the guide 159 with a curved flap supporting face 494.

100 On the opposite side of the carton and beneath the flap pressing member 492 is a similar supporting member 495 on the bed. The carton, Fig. 54, is fed by the carrier between the guides 158, 159 to a position between the flap supporting members 494, 495. In order to ensure 115 the proper positioning of the major flap so that the fingers 490 may engage it and infold it, we provide as a precaution, a vertically reciprocating plunger 496 in the guide 159 actuated by any convenient means, not shown, from the cam 120 shaft 129 already described.

110 As the shaft 476 rotates, the roll 479 lays a film of glue over the inner face of the outwardly extended major flaps 67^a, the outer faces of the infolded minor flaps 72^a, 73^a and the inner face 125 of the outlying major flap 68^a; the fingers 490 then pick up the flap, Figs. 56, 57, turn it inwardly, and the ribs 491 continue the infolding and pressing action over the infolded minor flaps. In order to prevent the glue applying 130 roll 479 from crushing the infolded minor flaps and carton edge walls, there is provided on a suitable support a short track 485, already referred to, which is sufficiently high to slightly raise the roll 479 on the shaft 478 by turning 135 the arms 480 about the shaft 481, Fig. 56, and so cause the roll 479 to pass lightly over the minor flaps without crushing them.

140 As the roll 479 drops after it leaves the track 485, it lays a film of glue over the inner face of the major flap 68^a, but the ribs 491 being narrow do not pick up glue therefrom in any quantity as they pass over it.

145 Top outer major flap closing means, station thirteen

150 For closing or folding the remaining major flap 68^a as the carton continues its travel after its mate 67^a has been folded by the fingers 490, Fig. 60, we have provided the following means.

- ing an electric circuit with a solenoid therein connected to the charging means, and a detector member constructed and arranged to contact with the carton if in normal position and otherwise if the carton is not in normal position, to close the circuit and lock the charging means in inoperative position. 5
7. In a carton opening, shaping, and closing, and liner making and inserting machine, means 10 for performing the foregoing steps and comprising in combination and operative relation a cutter for cutting the blank, a belt and rolls for feeding it to the liner forming plunger, a fixed blank guide adjacent thereto, and an oscillating guide for properly positioning the blank relative to the fixed guide in the path of the plunger; and means to fold the front and back liner top flaps down upon the liner body, and means subsequently to complete said liner 15 folding with the carton flap folding. 20
8. In carton liner making and inserting mechanism, means comprising in operative relation a cutter and a bed therefor to cut the liner blank, a belt and rolls for feeding it to the liner forming plunger, an oscillating guide for positioning the blank; and means, including a reservoir and a duct therefrom to the liner forming chamber, to supply the latter with a current of air for supporting the blank until 25 acted upon by the plunger. 30
9. In a packaging machine having means including a plunger for forming a liner for the carton, means for positioning the liner blank before the plunger including a fixed guide member, and a movable guide member for properly 35 adjusting the position of the blank relative to the fixed member, and means for operating the movable member. 40
10. In a machine of the class described having a carton carrier acting to carry the carton in a straight path therethrough, carton end closing means, and liner forming means including a liner blank cutter, driving means therefor, including a shaft, a driving member with 45 a pawl fast thereon, a second driving member loose on the shaft and driven from the first driving member; and means including an electric circuit with a carton detecting member therein operatively connected with the driving means of the blank cutter, to stop operation 50 of the latter when the detector finds no carton. 45
11. In a machine of the class described having a carton carrier acting to carry the carton in a straight path therethrough, carton end closing means, and liner forming means including a liner blank cutter; driving means therefor including a shaft, a driving member with a pawl fast thereon; a second driving means loose on the shaft and driven by said pawl; and means 55 including an electric circuit with a carton detecting member therein operatively connected with said pawl to stop the cutter when the detector finds no carton. 60
12. In a machine of the class described having means for feeding a collapsed carton, opening it, feeding it to a carton carrier, means for closing one carton end and carrying it in a continuous path through the machine, and liner forming means including a liner blank cutter; 65 driving means therefor including a shaft, a driving member with a pawl fast thereon; a second driving means loose on the shaft and driven by said pawl; and means including a movable detector normally in the path of a 70 carton and an electrical circuit including said
- detector and a magnetic switch and solenoid connecting the detector with the cutter, to stop the latter, said switch constructed to be operated by closing of the circuit if the detector finds no carton. 75
13. In a machine of the class described having means for forming sealing and inserting a liner in a carton including a heated plunger with a cross head and sprocket for operating it, liner blank positioning means including an air reservoir and an outlet therefrom to the liner forming chamber supplying a current of air beneath the liner blank. 80
14. In a machine of the class described having liner forming and inserting means, carton charging means and means for presenting the carton to the charging mechanism, carton detecting means including a carton detector normally in the path of the carton and means including an electric circuit and solenoid connecting the detector to the charging mechanism to control operation of the latter by the former; and separate liner closing means and subsequently acting carton closing means to form an independently closed liner. 85
15. In a machine of the class described having liner forming elements, and means for inserting it in a carton, mechanism for infolding the liner flaps within the carton comprising a progressively curved guide to turn an upright 105 carton flap to a horizontal position, an arm with a major-liner-flap-laying foot, and minor flap angular-outlining member with an angular contacting edge. 100
16. A machine of the class described having means for closing the liner top in a carton comprising an arm with a major liner-flap-laying-foot thereon reaching over one down-turned carton side flap, and operating means therefor. 110
17. A packaging machine comprising carton 115 opening means, a conveyor for the carton, end closing means, and liner forming and inserting mechanism comprising paper feeding mechanism, liner forming walls, a plunger acting to carry the paper between it and the said walls 120 to form two liner walls; and movable liner wall forming plates operable by the plunger to fold the paper against the remaining two sides of the plunger to complete the liner walls. 125
18. A packaging machine comprising carton 125 opening means, a conveyor for the carton, end closing means, and liner forming and inserting mechanism comprising paper feeding mechanism, liner forming walls, a plunger acting to carry the paper between it and the said walls 130 to form two liner walls; movable liner walls forming plates operable by the plunger to fold the paper against the remaining two sides of the plunger to complete the liner walls; and liner warming elements in the path of the liner 135 to warm the triangular folded tabs of the liner formed by the folding of the side walls to press them against the liner walls while the liner is on its way to the carton. 140
19. A packaging machine comprising a carton 140 feeding magazine, a carton guide, a member pressing the carton against the guide to prevent it from leaving the guide with the opener; a carton conveyor, lower flap gluing mechanism 145 swinging upward and gluing a major flap, and carton holding means acting to hold the carton in position during the gluing operation; swinging members receiving the lower major carton flaps from the gluing mechanism, one outside the flaps, one between them, and both members 150

swinging together in one direction to displace one flap and press its opposite flap against the infolded minor carton flaps, and said members swinging together in the opposite direction and 5 folding the remaining major flap upwardly against the first named major flap.

20. A packaging machine comprising a carton feeding magazine, a carton guide, a member pressing the carton against the guide to prevent it from leaving the guide with the opener; a carton conveyor, lower flap gluing mechanism swinging upward and gluing a major flap, and carton holding means acting to hold the carton in position during the gluing operation; swinging 10 members receiving the lower major carton flaps from the gluing mechanism, one outside the flaps, one between them, and both members swinging together in one direction to displace one flap and press its opposite flap against the infolded minor carton flaps, said members 15 swinging together in the opposite direction and folding the remaining major flap upwardly against the first named major flap; liner forming and inserting mechanism actuated by the progress of the liner to operate successively on the two sides of the liner to fold the free edges of the liner blank inwardly, and carton flap guides and liner electric heating means below the liner folding means respectively to seal the 20 liner and space apart the carton flaps to receive the liner; and cool air ducts positioned to introduce cool air into the liner preparatory to charging it.

21. A packaging machine comprising a carton feeding magazine, a carton guide, a member pressing the carton against the guide to prevent it from leaving the guide with the opener; a carton conveyor, lower flap gluing mechanism swinging upward and gluing a major flap, and 25 carton holding means acting to hold the carton in position during the gluing operation; swinging members receiving the lower major carton flaps from the gluing mechanism, one outside the flaps, one between them, and both members 30 swinging together in one direction to displace one flap and press its opposite flap against the infolded minor carton flaps, said members swinging together in the opposite direction and folding the remaining major flap upwardly against the first named major flap; liner forming 35 and inserting mechanism actuated by the progress of the liner to operate successively on the two sides of the liner to fold the free edges of the liner blank inwardly, and carton flap guides and liner electric heating means below the liner folding means respectively to seal the liner and space apart the carton flaps to receive the liner; cool air ducts positioned to introduce cool air into the liner preparatory to charging it; detecting means to ascertain the presence of a carton, charging means including a rotary charge leveller with a grooved wall acting to elevate and remove surplus material from the charge over the cup, tamping means to tamp 40 the material in the liner; laterally extended guides receiving and holding the major carton flaps from the path of infolding minor liner flaps, inwardly and downwardly acting helical and fixed folders for the latter; and swinging 45 inwardly and downwardly acting major liner flap folders, and a rolling major flap folder travelling over the flap and a second major flap folder acting upon the flap while the carton is moving beneath it.

22. A packaging machine comprising carton

conveying means for carrying the opened carton in a slightly distorted shape and having in combination therewith detector mechanism to register the approach of a carton to the liner forming means, liner forming means including 50 wall and closing members, means to supply a jet of air thereto to temporarily support the liner blank; and a plunger acting to force the blank between the liner forming means, wall folding members acting upon the blank to fold it about the plunger and selectively control thereby as to operation.

23. A packaging machine comprising, in combination, carton conveying means, liner forming means having resiliently mounted walls adjacent the liner to grip it to strip it from the plunger; a yielding support in the carrier for the liner to receive it and cause the liner lower end under pressure from the plunger to adhere somewhat to the carton end, a carton detector to 95 control the charging means including a member with a plurality of cam paths and roll therefor, and switch to control the line of travel of the roll and charging means.

24. In a machine of the class described having 100 a carton opener, a carton carrier, means to deposit the carton in the carrier, guides directing the carton in a continuous path, and liner forming means including a liner blank cutter; driving means therefor including a shaft, a driving 105 member with a pawl thereon; a second driving means loose on the shaft and driven by said pawl; and means including a movable detector constructed normally to contact with a carton if present, and means connecting the movable 110 detector with the cutter driving means permitting operation of the latter when the detector contacts with the carton, and carton top closing means.

25. In a machine of the class described having 115 a carton opener, a carton carrier, means to deposit the carton in the carrier, guides directing the carton in a continuous path, and liner forming means including a liner blank cutter; driving 120 means therefor including a shaft, a driving member with a pawl thereon; a second driving means loose on the shaft and driven by said pawl; and means including a movable detector constructed normally to contact with the carton if present, and means connecting the detector 125 with the driving means for stopping the latter when the detector finds no carton, and gluing means for closing the end of the carton.

26. In a machine of the class described having 130 carton opening and liner forming and inserting means, liner-minor-tab-forming means acting first to unfold the major flaps and subsequently the minor flaps, and liner-minor-tab-creasing means comprising a block with a forwardly and 135 downwardly inclined face and an outwardly forwardly inclined face acting to engage an outer carton minor tab face and raise it and press it against the liner-minor tab.

27. A machine of the class described having 140 means for closing a liner top in a carton, comprising an arm with a major liner flap laying and minor triangular tab folding member, a minor triangular tab completing member, and a minor carton flap and minor tab pressing member 145 cooperating with the tab completing member to position the carton and liner minor tabs for closing, and a rotary tab closing member, all operatively assembled, and operating means therefor.

EDWIN MOREY.
ROBERT H. STIMPSON. 150

CERTIFICATE OF CORRECTION.

Patent No. 1,943,770.

January 16, 1934.

EDWIN MOREY, ET AL.

It is hereby certified that error appears in the printed specification of the above numbered patent requiring correction as follows: Page 4, line 28, for "no" read not; line 110, for "spring" read springs; line 115, for "feeding" read feeling; and line 123, for "fell" read bell; page 10, line 82, claim 2, strike out the compound word "two-face" and insert the same after "flap" in same line of said claim; and that the said Letters Patent should be read with these corrections therein that the same may conform to the record of the case in the Patent Office.

Signed and sealed this 27th day of February, A. D. 1934.

F. M. Hopkins

(Seal)

Acting Commissioner of Patents.
